FRANCIS J. JOHNS, OF WILKINSBURG, PENNSYLVANIA, ASSIGNOR TO WESTINGHOUSE ELECTRIC & MANUFACTURING COMPANY, A CORPORATION OF PENNSYLVANIA

REVERSIBLE SQUIRREL-CAGE MOTOR HAVING LOW PLUGGING TORQUE

Application filed October 22, 1929. Serial No. 401,575.

My invention relates to polyphase, iron-core, squirrel-cage motors which are designed for use on large washing machines of the type requiring the motor to be reversed, by 5 plugging, approximately every ten seconds. A motor of the type specified must have a low plugging torque in order to eliminate jerking of the machine and strain on the gears or other drive mechanism; it must be quiet during the plugging operation; it must have a reasonably small slip at full load; and it should have certain other characteristics which will be pointed out.

My invention relates to a design of the slot 15 arrangements and other features of a motor of the character mentioned above to produce, for the first time, the characteristics just enumerated.

In the drawing, Fig. 1 is a full-scale, fragmentary, transverse sectional view of the rotor of a three-phase, 5-horsepower, 6-pole, 60-cycle, 1100-R. P. M. motor embodying my invention, and Fig. 2 is an enlarged view of a rotor slot with the conductor therein shown 25 in section.

In the drawing, the steel rotor punchings 2 of my motor are provided with a plurality of shallow openings or "slots" 3 in which are disposed the squirrel-cage bars 4 preferably 30 formed of hard-drawn copper and rectangular in cross-section. The bars 4 are buried in the rotor to provide a bridge 5 over each of the slots or openings 3, and each bridge has a radial slit 6 which is preferably as narrow, or nearly as narrow, as it is economically 35 practical to make it without unduly curtailing the life of the punching die and which extends upwardly from the top of the slot 3 to within a few hundredths of an inch 40 of the outer periphery of the punching 2. At present, I am making the slits between 31 and 50 mils in width, in the different motors embodying my invention.

After the rotor is finished and mounted 45 on its shaft, with the squirrel-cage bars 4 in place, its periphery is turned down, as indicated by the broken line 7 in the drawing, in order to make the periphery smooth and to adjust the air-gap to the desired depth, 50 which may be something like two hundredths

of an inch on each side of the rotor. This turning operation reduces the thickness of the solid iron bridge-portion 8 above the slit 6 to something of the order of 10 thousandths of an inch, which is sufficient to prevent the cutting tool from catching on the slit and small enough to so limit the degree of saturation of the solid iron bridge-portion 8 as to avoid any serious harmful effect. The metal bridge 8 is figured in my motor calculations 55 as having a slot factor of .5.

The attainment of desirable reversing motor characteristics, for the type of service hereinabove mentioned, has not been easy, and the steps which I have taken in its accomplishment constitute departures from all previous designs. Thus, while I shall attempt to point out, as well as possible, in the following explanations, my reasons for introducing certain design-limitations, or my 60 present theory as to the significance of certain design-limitations which may have been more the result of my own personal experience, rather than inductive reasoning, I do not wish to be limited to the theory herein- 65 after stated, and I desire it to be understood that these explanations constitute merely my own present views and theories of the matter.

The plugging torque is perhaps the most significant item of my reversible motor. 70 When I refer to plugging current and torque, I mean the current and torque which are obtained by reversing the terminals of one phase of the three-phase motor without any time-interval at the reversal and without any 75 resistance inserted in the primary phases.

According to some systems of control, there 80 may be a time interval of, say, not more than three seconds, and resistance may be included in the reversed primary circuits to be cut out 85 in steps by suitable control mechanism. These control systems have nothing to do with my present invention. I prefer to indicate the nature of my motor, however, by referring to its behaviour on plugging, by 90 which I mean that no time interval or primary resistance is utilized.

The plugging torque should be less than the starting torque and should preferably be between .7 and .85 of the starting torque, 100

whereas, in all squirrel-cage motors of previous design, the plugging torque has been of the order of at least one and three-quarters to two times the starting torque and, in double-deck squirrel-cage motors, the plugging torque has been three to four times the starting torque. In order to get the plugging torque down to the requisite value, I believe that it is necessary to strictly limit the depth 5 of the squirrel-cage bars which, in my design, are between .20 and .30 inches, because the eddy-current action tends to crowd the current into the tops of the bars, thus increasing the plugging torque, which is very strong, 10 even with ordinary bar-depths of around a half inch, at the double-frequency secondary conditions existing at the instant of plugging.

At the same time, the plugging current and the starting current must be made reasonably 20 small, in order to reduce the power drawn by the motor, and the disturbance on the line, as a result of its frequent reversals. My plugging current is something of the order of 15% more than the starting current, as 25 against plugging currents of 20% more than the starting currents in previous designs. My starting current is also lower than previous designs, ranging from 250 to 320% of the full-load current.

To reduce the starting current, it has been customary, inter alia, in the past, to add more turns to the primary winding, thereby materially reducing the primary flux and increasing the reactance of the machine. As the 30 starting current is almost all reactive, it is obviously reduced by this procedure, which is standard practice. In previous washing-machine motors for the class of service for which my present motor is designed, the gap 35 flux density has been about 16,000 to 23,000 lines per square inch, as compared with a gap flux density, in the standard or general-purpose motor of from 35,000 to 42,000 lines per square inch, running as high as 45,000 lines 40 per square inch in ordinary high-starting-torque motors.

In my present motor, I utilize only a slightly smaller flux density than in the standard 50 general-purpose motor, going down to an extreme lower limit of 26,000 or 27,000 lines per square inch and running up to gap densities of about 36,000 lines per square inch, in different embodiments of my invention.

I secure the reactance effect necessary to 55 reduce my starting current by means of the slot reactance of my deep-slit bridge which, in my motor, has a slot-factor (or ratio of the depth to the breadth of the slit) of from 2 to 8, to which is to be added, in each case, $\frac{1}{2}$ for the slot-factor of the solid-iron bridge-portion 60 8. In a rectangular bar, which is by far the preferable construction, being most economical of space, the slot-factor of the portion 65 of the slot in which the bar is located (or

the ratio of the bar-depth to three times the bar-width) is from .25 to .85 in my new motor. The ratio of the slot-factor of the bridge to the slot-factor of the bar, in my new motor, is very high, in order to introduce a rotor 70 reactance which will properly limit the starting current, ranging from values of 6 to 24 in my extreme design limits.

In general, I prefer to push the rotor-tooth density up to close to the highest practicable 75 limits, which are around 100,000 lines per square inch or more, or from about 80,000 to 120,000 lines per square inch; whereas, in previous designs of reversible washing-machine 80 motors, this rotor-tooth density has been smaller than 80,000 lines per square inch, with the result that the depth of the bars had to be made larger in order to get the requisite horsepower and other characteristics, which, in turn, meant a very appreciable 85 eddy-current effect on plugging, resulting in relatively large plugging currents and still larger plugging torques.

The item of quiet operation is one about 90 which very little is known. It can only be said that experience has shown that certain combinations of the number of rotor slots with certain numbers of stator slots in certain sizes of motors have been very good and others very bad, from this standpoint. If 95 any generalization can be made, I believe that the smaller slot-numbers on the rotor introduce the greater danger of noisy operation.

While I have described my invention in 100 a preferred form of embodiment, I do not desire to be limited thereto, except as indicated in the appended claims, when read in the light of the prior art.

I claim as my invention:

1. A polyphase iron-core squirrel-cage 105 motor having low plugging torque, characterized by having copper squirrel-cage bars and a slotted bridge over each bar; the slot-factor of the bridge being approximately between $2\frac{1}{2}$ and $8\frac{1}{2}$; the slot-factor of the bar being approximately between .25 and .85; the ratio of said slot-factors being approximately between 6 and 24; the gap flux density being approximately between 27,000 and 36,000 lines per square inch; the rotor 110 tooth density being approximately between 80,000 and 120,000 lines per square inch; and the bar-depth being approximately between .20 and .30 inch.

2. A polyphase iron-core squirrel-cage 115 motor having low plugging torque, characterized by having copper squirrel-cage bars and a slotted bridge over each bar; the gap flux density being greater than about 26,000 lines per square inch; the bar-depth being less than about .30 inch; and the ratio of the slot-factor of the bridge to the slot-factor of the bar being greater than about 6.

3. A polyphase iron-core squirrel-cage 120

motor having low plugging torque, characterized by having copper squirrel-cage bars and a slotted bridge over each bar; the squirrel-cage bars being substantially rectangular and having a slot-factor approximately between .25 and .85; the bridge having a slot-factor at least about 6 times that of the bar; and the bar-depth being less than about .30 inch.

10 4. A polyphase iron-core squirrel-cage motor having low plugging torque, characterized by having copper squirrel-cage bars and a slotted bridge over each bar; the bar-depth being less than about .30 inch; the slot factor of the bridge being greater than about $2\frac{1}{2}$; and the ratio of the slot factor of the bridge to the slot factor of the bar being greater than about 6.

15 5. The invention, as defined in claim 1, characterized by the fact that the slits in the bridges are closed at the air-gap periphery by an iron core-portion having a depth of the order of 10 mils.

20 6. The invention, as defined in claim 4, characterized by the fact that the slits in the bridges are closed at the air-gap periphery by an iron core-portion having a depth of the order of 10 mils.

25 In testimony whereof I have hereunto subscribed my name this 18th day of October, 1929.

FRANCIS J. JOHNS.
